[57] CLAIM

The ornamental design for a cover for a master cylinder cover, as shown.

DESCRIPTION

FIG. 1 is a front, top and side perspective view of a cover for a master cylinder cover showing our new design;

FIG. 2 is a top plan view thereof;

FIG. 3 is a side view thereof;

FIG. 4 is an end view thereof;

FIG. 5 is an end view thereof, opposite that of FIG. 4;

FIG. 6 is a side view thereof on a side opposite of FIG. 3; and,

FIG. 7 is a bottom plan view thereof.
